UNITED STATES PATENT OFFICE.

ALFORD CONNORS, OF UNIVERSAL CITY, CALIFORNIA.

VIOLIN-HOOK.

1,248,269.

Specification of Letters Patent.

Patented Nov. 27, 1917.

Application filed November 21, 1916. Serial No. 132,667.

To all whom it may concern:

Be it known that I, ALFORD CONNORS, a citizen of the United States, residing at Universal City, in the county of Los Angeles and State of California, have invented 5 new and useful Improvements in Violin-Hooks, of which the following is a specification.

This invention relates to means for supporting a violin to keep the violin in position beneath the chin of the player.

The object of the invention is to provide a device which may be easily and quickly attached to a violin, preferably by means of 15 the chin rest, for the purpose of supporting the violin in position beneath the chin of the player, the said means being designed to engage the player's collar whereby it may be readily adjusted in position.

20 With the above and other objects in view the invention consists of the following novel combination and arrangement of parts hereinafter fully described, illustrated in the accompanying drawings and pointed out in 25 the claims hereto appended.

In the drawings:

Figure 1 is a perspective view of a portion of a violin with the chin rest thereon and with the improved support in position, 30 the hook being illustrated engaged to a collar which is shown in dotted lines;

Fig. 2 is a sectional view through the chin rest securing means, illustrating the manner of engagement of the support therewith;

35 Fig. 3 is a detailed perspective view of the support.

Referring more specifically to the drawings, wherein like reference characters denote corresponding parts, the violin is 40 shown at 1, the chin rest 2 and the chin rest securing means at 3. The chin rest is of the usual or any preferred construction and is secured in position upon a violin by means of the usual clamping device shown, which 45 consists of violin engaging elements 4, and a sleeve 5, which is interiorly threaded for the purpose of lengthening or shortening the said elements.

The violin support as shown at 6 is formed 50 from a single piece of wire and comprises a hook 7 formed in the manner shown and adapted for engagement over the collar of the player, the hook 7 being adapted to lie

upon the inside of the collar. The support 6 is further formed with arms 8, which 55 when they are disengaged from the elements 4 are substantially parallel being formed of resilient wire. Formed upon the free ends of the arms 8 are laterally and outwardly extending semi-circular engaging 60 hooks 9, adapted for engagement around the elements 4 and when adjusted the support is securely held in position by the resilient character of the arms 8. The hooks 9 are engaged with the elements 4 at a point below the lower end of the sleeve 5, the said 65 sleeve acting as a stop to prevent any upward movement of the semi-circular engaging hook 9.

From the foregoing description taken in 70 connection with the accompanying drawings, it will be seen that the invention provides a support of an exceedingly simple construction which is capable of ready attachment to a violin and by means of which 75 the violin may be held in position beneath the chin of the player.

Changes in the form and proportion of the invention may be made without departing from the spirit thereof, and the right is 80 reserved to make such changes.

Having described the invention what I claims is:

1. The combination with a violin chin rest provided with attaching means therefor, of 85 a hook carried by said attaching means for engagement with the collar of the user.

2. The combination with a violin chin rest provided with attaching means therefor, of a spring hook supported by said attaching 90 means for engagement with the collar of the user.

3. The combination with a violin chin rest provided with attaching means therefor, of a detachable spring hook supported by said 95 attaching means for engagement with the collar of the user.

4. The combination with a violin chin rest provided with attaching means therefor, of a hook formed with spring arms for engagement with said attaching means, said hook being adapted for engagement with the collar of the user. 100

5. The combination with a violin chin rest provided with attaching means therefor, of 105 a hook provided with means engaging with

said chin-rest-attaching means, said hook engaging means contacting with a portion of the attaching means to limit the upward movement of the hook in one direction.

5. The combination with a violin chin rest provided with attaching means therefor, of a collar engaging member formed from a

single piece of spring wire and comprising a central hook portion, oppositely extending spring arms and hooks formed upon the free ends of said arms for engagement with said chin rest attaching means.

In testimony whereof I affix my signature.

ALFORD CONNORS.
